UNITED STATES PATENT OFFICE.

MAURICE LACHMAN, OF NEW YORK, N. Y., ASSIGNOR TO ELECTRO STEEL PRODUCTS CORPORATION, OF NEW YORK, N. Y., A CORPORATION OF NEW YORK.

METAL POLE.

Application filed July 2, 1920. Serial No. 393,626.

To all whom it may concern:

Be it known that I, MAURICE LACHMAN, a citizen of the United States, and a resident of New York, in the county of New York and State of New York, have invented certain new and useful Improvements in Metal Poles, of which the following is a specification.

This invention relates to the construction of metal poles for telegraph, telephone and other purposes.

The object of the invention is to construct a simple, light and strong metal pole which will be low in cost of manufacture and high in capacity to withstand the strains to which poles of this character are subjected.

The invention consists in the construction of metal pole as hereinafter more particularly described and then specified in the claims.

In the accompanying drawings, I have illustrated a pole constructed and arranged in the preferred form of the invention and in which—

Fig. 1 is a plan view of the blank from which the main element of the pole is formed.

Fig. 2 is a front elevation of a pole constructed in accordance with this invention.

Fig. 3 is a transverse vertical cross-section of the same taken on the line 3—3 and looking in the direction of the arrows.

Fig. 4 is a horizontal cross-section taken on the line 4—4 of Fig. 2.

Fig. 5 is a similar cross-section illustrating a modification in the arrangement of the side members.

In the drawings, 1 indicates a metal plate which forms the main element or body of the pole. The plate 1 is provided with tapered longitudinal edges so that the plate tapers from the bottom to the top or from one end to the other.

The plate along the tapered edges is provided with a multiplicity of cuts or slits 2 leaving tongues or ears 3 therebetween. Preferably the cuts 2 gradually enter further into the plate as they proceed from the top to the bottom whereby the resultant ears 3 are each of a more or less greater length as they approach the bottom.

The ears 3 along each longitudinal edge of the plate are bent laterally thereto, alter-

nate ears being bent to opposite sides of the plate and are preferably bent at right angles thereto.

4 indicates the side members of the pole and in the case illustrated they are in the form of angle iron uprights one of the flanges of which bears against the ears 3, 60 the other flange projecting outwardly as indicated in Fig. 4 or inwardly as indicated in the modification Fig. 5.

Two upright members 4 are disposed at each side of the pole and are located along each outer edge of the series of ears 3, thus connecting the ears together and due to the varying lengths of the ears the members 4 cause the pole as a whole to be tapered from end to end in side elevation. The taper of 70 the plate 1 gives a taper to the pole in front elevation.

The angle members 4 are firmly secured to the ears 3 by spot welding, riveting or any other suitable means.

What I claim as my invention is:—

1. A metal pole for telegraph, telephone and other purposes comprising essentially five upright load sustaining members consisting respectively of a main or central substantially flat upright metal plate extending from side to side of the pole and four side or peripheral members each consisting of an upright angle bar fastened by a flat face of one angle against the flat face of ears integral with and bent from the central plate, and tying the members against vertical displacement with relation to one another, said angle also strengthening the pole as a whole against bending or buckling by resistance in 90 the plane of the angle and ear and transversely to the general plane of the flat central member, the remaining angle of said upright bar serving to resist distortion in a general plane transverse to the first-named 95 plane.

2. A metal pole for telegraph, telephone and other purposes comprising essentially five upright load sustaining members consisting respectively of a main or central substantially flat upright metal plate extending from side to side of the pole and four side or peripheral members consisting of upright angle bars fastened by a flat face of one angle against the flat face of ears integral 100 with an bent alternately in opposite direc- 105

tions from the edges of the central plate, and tying the members against vertical displacement with relation to one another, said angle also strengthening the pole as a whole against bending or buckling by resistance in the plane of the angle and ear and transversely to the general plane of the flat central member, the remaining angle of said upright bar serving to resist distortion in

a general plane transverse to the first-named 10 plane.

Signed at New York in the county of New York and State of New York this 1st day of July A. D. 1920.

MAURICE LACHMAN.

Witness:

IRENE LEFKOWITZ.
